UNITED STATES PATENT OFFICE

FRANK T. NOWALK, OF SCRANTON, PENNSYLVANIA

JACK-HAMMER SUPPORT

Application filed May 3, 1928. Serial No. 274,935.

The present invention relates to improvements in jack hammer supporting devices, used in coal and like mines.

One of the important objects of the present invention is to provide a support for a jack hammer, whereby the latter will be held in a horizontal operative position, means being provided whereby said support is capable of vertical adjustment to various 10 heights.

A further object of the invention is to provide a jack hammer support of the above mentioned character, which includes a means for cooperation with the slotted handle of 15 the jack hammer to retain the tool on the table or bed of the support, while in use, additional means being provided for tending to reduce the vibration of the jack hammer while resting on the support.

20 Still a further object is to provide a jack hammer support that is bodily movable to bring the jack hammer into an operative or inoperative position, the support being further simple in construction, inexpensive, 25 strong and durable and further well adapted to the purpose for which it is designed.

Other objects of the invention will become apparent as the nature of the invention proceeds and when taken in connection with the 30 accompanying drawings.

In the accompanying drawings, forming a part of this application and in which like numerals designate like parts throughout the several views:

35 Figure 1 is a side elevation of the supporting means embodying my invention, showing the manner in which the jack hammer rests on the bed or table of the support, the hammer being shown in operation.

40 Figure 2 is a top plan view of the support with the hammer mounted thereon.

Figure 3 is a detail perspective view of the base of the support, and

45 Figure 4 is a detail perspective view of the angular clip that is detachably secured to the upper end of the vertical arm that projects from one end of the bed or table supporting plate.

In the drawings, wherein for the purpose 50 of illustration is shown the preferred em-

bodiment of my invention, the numeral 1 designates generally my improved support, the same comprising a rectangular shaped wooden base 2.

Secured on the upper portion of the central portion of the base is the flanged internally threaded socket member 3, the flange 4, thereof being formed with spaced openings to receive fastening screws 5 that are driven into the top of the base as clearly 55 shown in Figure 3 of the drawings.

A telescopic standard forms a salient part of the present support, and this telescopic standard includes a lower tubular section 6, which is externally threaded at its lower end 65 for threaded engagement within the threaded socket 3, and the lower end of this section 6, engages with the top face of the base 2. This is also shown very clearly in Figure 3 of the drawings. The upper end of the 70 lower section 6 is slidably disposed in the lower end of the elongated tubular intermediate section 7, and a set screw 8 is threaded through an opening in the side of the lower portion of the intermediate section for engagement with the upper portion of the lower section for adjusting the adjacent ends of these sections together. One or more of these set screws may be provided as is clearly 75 shown in the drawings.

80 The telescopic standard further includes the upper tubular section 9 that has its lower end slidably disposed in the upper end of the intermediate section 7 and set screws 10 which extend radially through the upper 85 portion of the intermediate section engage with the lower end portion of the upper section 9 to adjustably secure the upper section.

In this manner, the standard may be adjusted to any desired height.

85 The upper end of the uppermost section 9 is externally threaded for engagement within a threaded opening formed in the central portion of a horizontal plate 11, and as is clearly shown in Figure 2, the plate 11 is disposed transversely with respect to the rectangular shaped base 2. The rear end of the plate 11 is disposed upwardly as at 12, and the purpose thereof will be presently described.

A substantially rectangular shaped wooden 100

table or bed 13 is secured on the upper face of the metallic plate 11, in any appropriate manner, and upon this bed or table is adapted to rest in a horizontal manner, the jack hammer designated generally by the letter A. The jack hammer is of the conventional construction and is provided at its rear end with the handle B, and in this handle is formed the hand hole C, and the upwardly disposed rear end portion 12 of the plate 11 is adapted to extend through the hand hole as clearly indicated in Figures 1 and 2 of the drawings.

For the purpose of preventing undue vibration of the jack hammer while the same is in operation, I provide the substantially right angular shaped clip shown generally at 14, in Figure 4. The vertical side of this clip is formed with an opening 15 that registers with a similar opening formed in the upper end portion of the upwardly disposed rear end 12, and a bolt 16 extends through the openings. A nut 17 is threaded on the threaded end of the bolt for securing the clip in a stationary position, and the horizontal portion of the clip will engage with the handle portion B of the jack hammer A in the manner as clearly shown in Figures 1 and 2 of the drawings.

The base 2 is adapted to rest for slidable movement on the planks 18, that rest on the floor of the mine B, and when in operation, the stand or support with the jack hammer A secured on the bed or table 13 will be bodily moved along the planks so that the drill E associated with the jack hammer A will be forced into the wall of the mine.

It will thus be seen from the foregoing description that I have provided a jack hammer support that can be readily and easily adjusted to various heights and furthermore due to its simplicity, the jack hammer can be easily and readily secured on the bed or table in a positive and efficient manner.

While I have shown the preferred embodiment of my invention, it is to be understood that various changes in the size, shape and arrangement of parts may be resorted to, without departing from the spirit of the invention and the scope of the appended claims.

What I claim as new is:

1. In a support for a jack-hammer, the combination of a base, a standard rising from said base, a transversely disposed plate mounted on the upper end of said standard, a bed supported on said plate and upon which the jack hammer is adapted to rest, said plate at one end thereof terminating in an upwardly disposed vertical end portion adapted to extend through the hand hole in the handle of the jack-hammer, and a resilient clip detachably secured on the upper end of the said vertically disposed portion of said plate for frictional engagement with the top portion of the handle of said jack-hammer adjacent the hand hole of said handle.

2. In a support for a jack-hammer, a plate, supporting means therefor, said plate adapted to support thereon a jack-hammer, said plate having a projection extending therefrom at right angles thereto, said projection adapted to extend through the hand hole of the jack-hammer handle, and a resilient clip mounted on said projection and engaging said jack-hammer for yieldably retaining said projection in said extended position through said hand hole of the said jack-hammer handle.

In testimony whereof I affix my signature.

FRANK T. NOWALK.
